UNITED STATES PATENT OFFICE.

PETER BAGLEY, OF FARNWORTH, ENGLAND.

UMBRELLA.

1,239,757.

Specification of Letters Patent. Patented Sept. 11, 1917.

Application filed October 5, 1915. Serial No. 54,251.

To all whom it may concern:

Be it known that I, PETER BAGLEY, a subject of the King of Great Britain, residing at Farnworth, Lancaster, in the Kingdom of England, have invented certain new and useful Improvements in Umbrellas; and I do hereby declare the following to be a full, clear, and exact description of the invention, such as will enable others skilled in the art to which it appertains to make and use the same.

This invention relates to umbrellas, and one of the principal objects of the invention is to provide an umbrella which can be readily taken apart and packed in a small compartment, and which can be readily assembled to form an umbrella which will not in general appearance be distinguishable from the ordinary umbrella.

Another object of the invention is to provide an umbrella in which the stick is made in sections, and in which the ribs, the braces, and the top notch are detachable from the stick, and the cover is detachable from the ribs, so that the entire umbrella may be readily assembled and quickly taken apart for packing.

The foregoing and other objects may be attained by means of the construction illustrated in the accompanying drawings, in which—

Figure 1 is a view in elevation of the umbrella frame and stick with the cover removed and the umbrella closed.

Fig. 2 is a sectional view taken through the center of the cover, and the umbrella shown opened out, with the handle portion of the stick broken away.

Fig. 3 is an enlarged sectional view of the top notch.

Fig. 4 is a detail view showing the clasp for holding the two members of the stick together,

Fig. 5 is a detail elevation of one of the sockets connected to the cover for connection to the ends of the ribs,

Fig. 6 is a view showing a portion of the cover in section, and the socket member connected thereto, and shown in side view,

Fig. 7 is a detail section showing one of the clips connected to the cover for engaging the ribs of the umbrella frame.

Fig. 8 is a view in elevation showing the top notch and the manner of connecting the same to the ferrule near the top of the stick, and

Fig. 9 is a sectional view showing the clasp for holding the two members of the stick together.

Fig. 10 is a fragmentary view of all the parts assembled,

Fig. 11 is a fragmentary sectional view.

Referring more particularly to the drawings, the numeral 1 designates the lower and 65 2 the upper section of the stick of my collapsible umbrella. The section 1 is provided with an enlargement at its lower end, which constitutes a handle. The sections 1 and 2 are detachably connected together by means of a clasp 7, which will be hereinafter 70 more fully described.

The section 1 has secured to its upper end the sleeve 3, which is provided with an opening 4. The upper section 2 is provided near its lower end with a similar sleeve 5, and the section 2 has its lower end reduced as at 5' around which is secured a sleeve 6, which sleeve is adapted to telescope in the sleeve 3 carried by the lower section 1. A spring clasp 7 above mentioned is connected 80 to the sleeve 6 carried on the reduced portion 5' and it is provided with an enlarged portion 8 which constitutes a head and this head is adapted to fit in the opening 4 in the sleeve 3 and thus hold the handle member 1 and upper section 2 detachably connected together. The sleeve 3 is provided with a lug 7' and the sleeve 5 has a recess 8'. The lug 7' is adapted to fit when the two sections are forced together thus preventing the rotation of one section relatively 90 to the other.

A top notch 9 is removably and slidably mounted on the upper section 2 and has pivotally secured thereto a plurality of ribs 95 10. The top notch 9 is provided at diametrically opposite points with interior recesses 11 and 11^a, the purpose of which will be hereinafter more fully described.

The top notch 9 is also provided with exterior recesses 11^b and 11^c at diametrically opposite points.

A ring 13 is provided at diametrically opposite points with pivoted catches 12 and positioned in the central opening in the cover 14 and the cover is secured to the edges thereof. Above the ring is clamped the flaring collar 15, which collar is provided with depending fingers 16, which fingers have their lower ends provided with outwardly projecting lugs 17. The outwardly projecting lugs 17 of the flaring collar 15 are adapt-

ed to be positioned through the ring 13 and engage the underside thereof thus holding the cover securely wedged between the ring 13 and the flaring collar 15.

5 A collar 18 is rigidly connected to the upper section 2 and is provided with an annular flange on its upper edge, which flange is designated 19. The collar 18 is provided at diametrically opposite points with exterior lugs 11' and 11'' which are adapted to be inserted in the recesses 11 and 11^a which are in the top notch 9 when the top notch 9 is forced up thereon. The top notch 9 is held against movement from the collar 18 by the forcing of the pivoted catches 12 into the recesses 11^b and 11^c of the top notch 9 and thus holding the same against downward movement.

20 The annular flange 19 is also provided at diametrically opposite points with recesses which are adapted to permit the shank portions of the catches 12 to fit therein, this permitting the same to be firmly inserted under the top notch 9 and hold the same against movement.

25 It can be readily seen that due to the fact that the ring 13 is held against movement with relation to the flaring collar 15 that the top notch 9 and collar 18 will be held against movement by the catches 12.

30 The ribs 10 are provided intermediate their ends with pivoted braces 20, which braces have one of their ends pivoted to lugs 21, which lugs are carried by the rib 10. 35 The free ends of the braces are attached to runners 22 which are provided with slots 23, which slots are adapted to be engaged by the spring 24 which is carried by the upper section 2 of the detachable umbrella when 40 the umbrella proper is in a raised position.

45 The cover 14 is provided with a series of spring clasps 25 which are adapted to snap or engage the ribs 10 at suitable points to hold the ribs into engagement with the cover 14. The outer ends of the cover are provided at spaced distances with socket members 26 which are adapted to engage over the pointed outer ends of the ribs 10, said socket members being cut-away as at 27 and secured to the cover 14 by suitable fastening means such as a clasp or the like.

50 The manner of assembling the parts to form the umbrella may be briefly described as follows:

55 The upper section 2 of the stick is pushed

down through the top notch 9 and collar 18 and its reduced end carrying the sleeve is forced in the sleeve carried by the member 1 and the same are held against separation by the snapping of the spring clasp 7 in the plate.

60 The cover 14 is fastened to the ring 13 and carrying the flaring collar 15 is then placed over the upper section 2 and the catches 12 carried by the ring 13 are snapped into their respective recesses in the top notch 9 thus holding the parts assembled. It can be thus seen that in this position the umbrella is ready for use and when it is desired to carry the umbrella in a small package or compartment the sections 1 and 2 may be readily disconnected and the cover 14 removed by releasing the catches 12 of the top notch 9 and the various parts readily folded and placed in a small package.

65 Various changes may be made in the details of construction without departing from the spirit and scope of the invention as defined in the claims.

70 What is claimed is:

75 1. An umbrella comprising a stick made up in sections and connected together by means of a spring clamp, a top notch, ribs pivoted to the top notch, a runner, braces pivoted to the ribs and runner, said top notch and runner being detachable from the upper section of the stick, a cover provided with a ring having pivoted latches thereon to connect with the top notch, and means for connecting the cover to the ribs.

80 2. An umbrella comprising a stick in two sections, a top notch having ribs pivoted thereto, braces connected to the ribs, a runner to which the braces are connected, a cover having sockets for the ends of the ribs, and clasps to engage said ribs, a ring connected to the center of the cover and provided with hinged latches to engage the top notch to which the ribs are pivoted, a collar detachably secured to the top notch, and a 85 collar fitted over the top of the ring, and latches carried by one of the collars and engaging the opposite collar for holding the parts assembled.

90 In testimony whereof I affix my signature in presence of two witnesses.

95 PETER BAGLEY.
